Primary Examiner — Carol P Rademaker(74) *Attorney, Agent, or Firm* — H. Frederick Rusche;
Husch Blackwell LLP(57) **CLAIM**

I claim the ornamental design for a bottle, as shown and described:

DESCRIPTION

FIG. 1 is a top, front, and left side perspective view of a bottle showing the new design;

FIG. 2 is a front elevational view thereof, the rear elevational view being a mirror image;

FIG. 3 is a left side elevational view thereof;

FIG. 4 is a right side elevational view thereof;

FIG. 5 is a top plan view thereof; and,

FIG. 6 is a bottom plan view thereof.

The broken lines shown in the drawings are included for the purpose of illustrating environmental structure and form no part of the claimed design.
